Patented May 4, 1920.

2 SHEETS—SHEET 2.

UNITED STATES PATENT OFFICE.

FREDERICK MYERS, OF NEW YORK, N. Y., ASSIGNOR, BY DIRECT AND MESNE ASSIGNMENTS, TO MYERS PHONOGRAPH CORPORATION, A CORPORATION OF NEW YORK.

TONE-MODULATOR FOR PHONOGRAHS.

1,338,950.

Specification of Letters Patent.

Patented May 4, 1920.

Application filed December 12, 1918. Serial No. 266,384.

To all whom it may concern:

Be it known that I, FREDERICK MYERS, a citizen of the United States, and a resident of New York, in the county of New York and State of New York, have invented certain new and useful Improvements in Tone-Modulators for Phonographs, of which the following is a specification.

This invention relates to improvements in phonographs, especially those using flat disk records, and has as its special object to provide means whereby the issuing sounds may be increased or diminished in volume at the will of the operator and in a positive manner.

Another object is to provide a tone modulator of novel design that can be applied to any of the usual types of talking machines without detracting from their appearance, and at a moderate cost.

These and other like objects are attained by the novel construction and combination of parts hereinafter described and shown in the accompanying drawings, forming a material part of this disclosure, and in which:—

Figure 1 is a fragmentary top plan view of a conventional type of phonograph showing an embodiment of the invention.

Fig. 2 is a vertical sectional view taken on line 2—2 of Fig. 1.

Fig. 3 is a transverse sectional view taken on line 3—3 of Fig. 2.

Fig. 4 is a vertical sectional view taken on line 4—4 of Fig. 2.

Fig. 5 is a sectional view taken on line 5—5 of Fig. 4.

Fig. 6 is a perspective view of the tone arm stand and connected parts, and

Fig. 7 is a perspective view of the tone arm engaging sleeve.

In the drawings the level, flat top of the phonograph casing is indicated by the numeral 10, said casing containing mechanism for rotating the spindle 11 and turn-table 12, on which is disposed the records to be played.

A needle 14 is mounted as usual in the head or sound box 15, containing the diaphragm, the sound passing therefrom into and through a tubular chamber 17 engaged with a conical tubular arm 18.

At the outer, larger end of the arm 18 is formed a short longitudinal recess 20, ter-

minating in a transverse slot 21, the ends of which are engageable with a pin 23 fixed in the upper side of a hollow conical support 24, adapted to be snugly received in the arm 18 and extending outward from a vertical bar 25, having an arcuate interior surface 26.

This bar is carried by and constitutes a section of a sleeve 28, said bar being secured to said sleeve by pivot screws 29 in such manner that the arm 18 may be raised, together with the needle, in a convenient manner.

The interior of the sleeve 28 and surface 26 of the bar 25 normally engage with the exterior of a cylindrical shell 30, having a partially closed top 31, its lower end being tightly engaged in an annulus 32 extending up from a bracket 33, having an extension 34 passing through the cover 10.

This bracket is formed with a flat extension 35 and is secured to the cover by screws 36. At the end of the extension 35 is a raised boss 38 to which is fitted a screw 39, acting as a pivot for the hub 40 of a lever 41, having an offset handle 42 extending closely adjacent to the cover 10 and separated therefrom by a felt pad 43 which acts to restrain the lever against free movement.

Carried at the opposite end of the lever 41 is a gear segment 45, its teeth meshing with corresponding teeth on a segment 46 fixed upon a ring or band 47, rotatably mounted on the annulus 32, the latter having in it a slot 48 through which passes the point of a screw 49, set in the band 47, to limit the movement of the band and at the same time transmit rotary motion therefrom to the shell 30.

A block 50 of cork or like soft, elastic material, having a beveled upper surface 51, is fixed in the shell 30, which, by action of the handle 43, may be rotated so as to either partially, or wholly, cover the passage through the arm 24, thereby interrupting the sound.

From the foregoing it will be seen that an effective and easily operated tone modulator has been described, together with the manner of its application and use, and it will be evident that the construction shown is merely illustrative, permitting modification to be made without departing from the general scope of the appended claims.

Having thus described my invention, what I claim as new, and desire to secure by Letters Patent, is:—

1. In a device of the class described, 5 the combination with a phonograph having a hollow tone arm, a casing, and a tubular vertical support for said arm extending up from said casing, of a rotary plug mounted within said support adjacent the outlet of said tone-arm and adapted to control the sound passage through said support, and a lever pivoted on a fixed part of the machine for actuating said plug.
2. In a device of the class described, the 15 combination with a tubular tone arm support, of a shell rotatable in said support, a pliable plug in said shell adapted to control the sound passage through said support, a sleeve circumjacent to said support, a segmental gear on said sleeve, a lever pivoted on a vertical axis, a segmental gear on said lever engaging with the first named gear, and means for manually operating said lever, whereby said plug may be turned.
3. In a device of the class described, the 20 combination with a phonograph, a casing therefor and a tone arm, of a hollow stand upon which said tone arm is mounted to rotate on a vertical axis, a cylindrical shell 25 rotatable in said stand, a sleeve rotatable on said stand, operative connections between said shell and sleeve, a plug in said shell, said plug being adapted to act as a shutter for the passage through said stand, a lever 30 pivoted on said casing having a handle portion extending therebeyond, and an operative connection between the inner end of said lever and said sleeve whereby the latter 35 may be partially rotated.
4. In a device of the class described, the 40 combination with a phonograph having a casing and a hollow tone arm stand extending above said casing, of a sectional sleeve rotatable on said stand, one section of said 45 sleeve being pivoted on a horizontal axis on the other section, a tubular extension formed with said pivoted section, and a tone arm engageable with said extension.
5. In a device of the character described, 50 the combination of a tone-arm, a tubular support therefor, and a rotary plug extending longitudinally within said support adjacent the outlet of said tone-arm.
6. In a device of the character described, 55 the combination of a tone-arm, a tubular support therefor, and a rotary plug mount-
- ed within said support and having a beveled end adjacent the outlet of said tone-arm.
7. In a device of the character described, 60 the combination of a tone-arm, a tubular support therefor, a rotary valve plug within said tone-arm and movably mounted in said support, and means for operating said valve plug mounted on a fixed part of the machine whereby the same may be adjusted while the machine is in operation without interfering with the operation of said tone-arm.
8. In a device of the character described, 70 the combination of a tone-arm, a tubular support therefor, valve means extending longitudinally within said tone-arm and movably mounted in said support, and means exteriorly of said tone-arm for adjusting said valve means.
9. In a device of the character described, 75 the combination of a tone-arm, a tubular support therefor, valve means within said tone-arm and movably mounted in said support, a sleeve on said support operatively connected to said valve means, and means to rotate said sleeve and thereby adjust said valve means.
10. In a device of the character described, 80 the combination of a tone-arm, a tubular support therefor, valve means within said tone-arm and movably mounted in said support, a sleeve on said support operatively connected to said valve means, gear teeth on 85 said sleeve, and a sector in mesh with said teeth for moving said sleeve and thereby adjusting said valve means.
11. In a device of the character described, 90 the combination of a tone-arm, a tubular support therefor, a shell rotatable in said support and extending within said tone-arm, valve means carried by said shell, and means to rotate said shell and thereby adjust said valve means.
12. In a device of the character described, 95 the combination of a tone-arm, a tubular support therefor, a shell rotatable in said support and extending within said tone-arm, valve means carried by said shell, means rotatable with respect to said support for rotating said shell and thereby adjusting said valve means, and a lever for rotating said last-named means.

In testimony whereof I have signed my name to this specification.

FREDERICK MYERS.
